UNITED STATES PATENT OFFICE.

CHARLES A. MUNGER, OF NEW YORK, AND ARTHUR P. YATES, OF SYRACUSE, N. Y.; SAID YATES ASSIGNOR TO SAID MUNGER.

IMPROVEMENT IN OIL-TANKS.

Specification forming part of Letters Patent No. 176,665, dated April 25, 1876; application filed March 22, 1876.

To all whom it may concern:

Be it known that we, CHARLES A. MUNGER, of the city of New York, in the county and State of New York, and ARTHUR P. YATES, of the city of Syracuse, in the county of Onondaga and State of New York, have invented a new and useful Improvement in Tank-Cans for Oil and other Liquids, of which the following is a specification:

The primary object of the present invention is the production of an improved tank-can of superior compactness and simplicity of construction, which will at the same time possess the required functions, and be adapted to be used with superior convenience and efficiency.

The invention consists, first, in a flat, or nearly flat, horizontal cover, having a fixed rear portion, which is adapted to support the measures in convenient position; secondly, in a horizontal partition or floor, supported parallel, or nearly parallel, to the top, and provided with a hinged drop to form the bottom of the sink or pump-chamber, and to provide for readily cleaning the reservoir beneath it; thirdly, in an adjustable pump, adapted to be elevated or extended to a convenient height for use when the tank is opened, and to have its head dropped vertically when the tank is to be closed, so as to be covered by a low horizontal lid; fourthly, in automatic means for extending the pump-tube to the bottom of the reservoir when the adjustable pump is elevated, as hereinafter set forth.

Figure 1 is a plan view of an improved tank-can illustrating this invention. Fig. 2 is a vertical section on the line 2 2, showing the cover open and the pump-head elevated, as in Fig. 1. Fig. 3 is a plan view of the same tank-can closed. Fig. 4 is a vertical section on the line 4 4, Fig. 3. Fig. 5 is a sectional representation of a modified form of the adjustable pump.

Like letters of reference indicate corresponding parts in the several figures.

This improved tank-can is intended, like others of the same general class, for the use of retailers and large consumers of kerosene or coal-oil and other liquids, and to be made chiefly of galvanized iron or tin-plate, and of various sizes, graded as to capacity to suit the demand.

A cylindrical shell, *a*, of the proper dimensions, is constructed with parallel ends, and is provided with a flat bottom, *b*, below which the wired lower edge of the shell has been extended to receive a wooden backing or outer bottom, *b*², as shown. The upper end of the shell is provided with a flat, or nearly flat, circular cover, composed of a fixed rear portion, *c*, and a movable front cover or lid, *c*². The former is adapted, besides its primary function, to serve as a support for measures while the tank is open, or at all times. To especially adapt it for this use, the fixed section *c* of the cover has been depressed at its front edge, or at the middle of the top, sufficiently to cause it to shed the drippings, and provided with radial conducting-grooves, the latter leading to a central drip orifice or passage, which, in the illustration, is formed by an eyelet, *d*, serving, primarily, as a pivotal rivet to unite the two parts of the cover. A knob, *e*, accommodated in one position by a notch, *f*, in the fixed section, facilitates moving the lid *c*², which turns horizontally on its pivot *d*, and occupies a position beneath the fixed section when the cover is opened, as shown in Figs. 1 and 2. The fixed section is supported beneath the inturned wire of the upper edge of the shell. The pivoted lid is supported beneath by a continuous parallel wire, *g*, and above, when closed, by another wire, *g*², extending around the outside of the front opening, as shown in Figs. 2 and 4.

To divide the interior of the tank into a reservoir, *A*, and a sink or pump-chamber, *B*, above the reservoir, a horizontal partition or floor, *h* *h*², is employed, and to give convenient access to the reservoir to facilitate cleaning the tank the front portion *h*² of this floor is attached to the fixed rear portion by hinges *i*, so as to form a drop.

A pair of staples, *j* *j*², the one passing through the other to receive a locking-pin, hold this drop in its normal position, where it serves to support the measures while they are being filled, the fixed staple *j*² being attached to the shell *a*. A staple, *j*³, on the bottom of the drop passes through an orifice, *k*, in the fixed section *h* of the floor, when the drop is folded back beneath this, and receives a locking-pin above it, as indicated in dotted

lines in Fig. 2. The drop is thus readily fastened in either position. The chamber B, as a whole, will accommodate all the measures and the funnel or funnels which usually accompany the tank during storage and shipment, and may be adapted to hold them also while the tank is not being used.

For drawing the oil or other liquid a pump, P, is provided, which, besides its adaptation to be supported and extended, as hereinafter set forth, may be of any ordinary or approved construction. A strainer, s, for returning the overflow and pump-drip to the reservoir, is arranged in the drop h^2 , as shown in Fig. 1. A fixed pump-support attached securely to the inside of the shell a has horizontal top and bottom plates, $l m$, and a vertical side plate, n , and the former are provided with an orifice, o , (shown in Fig. 5, and in dotted lines in Figs. 1, 2, and 4,) within which the pump, or the upper portion of the pump, is adapted to slide and rotate. The top and bottom plates are supported at the orifice o by a longitudinally-grooved tube, which forms the walls of the said orifice, as shown in Fig. 5. The pump-support is located at the right-hand side of the tank, and is segmental in form, and is supported within a corresponding orifice in the sink-floor h h^2 , so as to project above it; but it may be located wholly above or below the floor, if preferred, or with its upper surface level with the floor, and in the latter case a collar or sleeve of the required length may take the place of the bottom and side plates $m n$. The pump-support may also be extended back for additional strength, as indicated by dotted lines in Fig. 2. For supporting the head of the pump in elevated position the neck or upper end of the pump-tube is provided with a pair of lateral lugs, p p^2 , which may be in the same or different vertical planes.

When the pump or pump-head is turned into one position, (indicated in Fig. 4, and by dotted lines in Fig. 1,) the upper lug p coincides with a corresponding enlargement of the orifice o , and the pump or pump-head can be lifted until this lug appears above the pump-support. A partial rotation of the pump or pump-head then locks it, and moves the nozzle to its effective position, the respective lugs passing above and below solid portions of the top and bottom plates of the pump-support. Released in the same manner, the pump can be readily withdrawn altogether preliminary to filling or cleaning the tank.

In the elevated position of the pump-head the gallon measure is accommodated beneath the nozzle, as indicated in Fig. 2. When the head is lowered upon the pump-support the low horizontal lid c^2 works freely above it, and incloses it, as illustrated in Fig. 4.

The pump-tube is adapted to extend itself to the required length, so as to reach always to near the bottom of the reservoir, by a flexible extension-tube, t , Figs. 2 and 4, having

the lower valve v at its extremity, and, in a modification, by a packed telescopic joint, t^2 , as shown in Fig. 5. In the latter arrangement the lower portion of the pump-tube is held in position against movement with the head, and in the illustration this is accomplished by means of a hook brace or strut, x .

The reservoir is conveniently filled through the orifice o in the pump-support by inserting a funnel therein and pumping into the funnel.

We have particularly described and illustrated our preferred construction, which obviously admits of modifications in unessential particulars.

The only details of mechanical construction which are considered essential to the several parts of the invention, respectively, are specified, or necessarily implied, in the claims following.

Our improved cover provides for the accommodation of the measures on the top of the tank above the movable cover of the pump-chamber, so that the cover can be opened and closed at will without disturbing them. At the same time it provides a convenient form of cover which is never in the way, and simplifies the construction of the tank, shortens it so as to adapt a tank of given diameter and capacity to set beneath a lower shelf, and facilitates packing the tank for storage and shipment. A material saving in metal, time, and space, and in the consequent cost of manufacture and shipment, is thus effected, while a superior article is at the same time furnished.

The following is claimed as new and of this invention, namely :

1. The flat horizontal cover c c^2 , forming the top of the tank, and composed of a fixed rear portion and a pivoted front portion or lid, the latter turning horizontally above the pump-chamber and beneath the flat rear portion of the cover, in combination with a pump which is covered by said lid when the tank is closed, substantially as illustrated and described, for the purpose specified.

2. The sink-floor h h^2 , having the segmental drop h^2 , hinged, and provided with holding devices, substantially as shown, for the purpose set forth.

3. The adjustable pump-head, adapted to slide vertically, so as to occupy an elevated or a lowered position, and arranged within a tank-can, substantially as herein set forth.

4. The combination of the fixed pump-support l o , the vertically-adjustable pump P, and the extension-tube t , substantially as shown and described.
